BUILDING CONSTRUCTION

Salvator S. Calafati, New York, N. Y., assignor of
 three-fourths to Salvator S. Calafati, Jr., and
 one-fourth to John M. Cole, both of New York,
 N. Y.

Application July 6, 1932, Serial No. 620,997

28 Claims.

(Cl. 72—1)

The present invention relates to building construction and more particularly to the construction of buildings such as one, two, and three story dwellings, barns, garages, sheds and the like. Certain features of the present invention may also be employed in the construction of partitions in steel, brick or concrete buildings.

The conventional layouts of buildings of the class referred to, requires the use of a foundation, generally some form of masonry. Vertical side walls at right angles to one another, (or rarely walls with 45° or 135° angles to one another). The roofs are preferably sloping. Floor plans, room sizes and layouts vary to suit the architect or owner and are subject to infinite variation.

The present invention contemplates improvements in building construction whereby buildings of the type referred to may be constructed out of factory built units and preformed parts designed to be assembled in a practically unlimited number of designs so that the architectural design of the building need not be confined to any preconceived notion of floor lay out, exterior or interior finish, or roof design.

In order that the economies available from factory built units and parts may be had throughout the entire building, the design of the entire building should be considered as a unit. The foundation, of any approved form, is arranged to support a sill forming member (preferably steel) designed to receive the floor system and the wall system. The floor system employs preformed metal beams of fixed, standard dimensions together with wooden floor timbers also of fixed, standard dimensions. The sills and beams are designed to be assembled without any cutting or fitting and the wooden floor timbers are pre-cut to fit the floor beams. Any form of flooring may be used. The wall system for the outside walls is made up of rectangularly shaped units having metal frames designed for ready securement to the sills, to interlock with one another, form inside and outside corners, and provide window and door openings with the necessary door and window frames. All these frames are covered inside and outside with thick insulating board so that the walls and partitions are strong and substantial, sound-proofed and thermally insulated. The wall forming units are designed to receive this insulating material and hold it in place to form tight corners, both inside and outside. The upper ends of the wall forming units support a plate, similar to the sill, and this plate supports the floor system for the second floor and the wall system for the second floor. Partitions may be provided by placing selected partition forming units or sections in selected positions, which need not correspond with those of the floor below; and overhangs or set backs worked into the design if desired. These wall

and partition units are covered with insulation board in the same way as those forming the walls and partitions of the lower story. They support a roof plate somewhat like the second floor plate, but designed to receive rafters as well as wall forming units for the gables and a ceiling for the second floor. Any conventional roof may be employed, but I prefer to employ a roof construction such as shown in my application for roofs for buildings, filed concurrently herewith. Any conventional outside finish or veneer may be applied to the insulating board forming the outer walls, and conventional inside finishes applied directly to the inside walls and partitions without the use of lath or plaster, thereby materially shortening the time required for completing the building.

In the design of the factory built units and preformed parts contemplated by the present invention, it is desirable for economical use of materials, accuracy of fit, ease of assembly and flexibility of design, to arbitrarily select a unit dimension which will permit the architect to obtain rooms, closets, foyers, halls, doorways, window openings and the like of conventional size and appearance. For purposes of illustration, the arbitrary dimension of 1' 9" is selected as the smallest unit in laying out the floor plan. Multiples of this dimension are 3' 6", 5' 3", 7', 10' 6", 12' 3", 14', 15' 9", 17' 6", etc., and hence it is obvious that, by employing wall forming sections of this unit width, and multiples thereof, that rooms and closets of the above dimensions (less wall thicknesses), may be had. Such dimensions allow for a floor plan with practically any conventionally sized room. If a finer gradation of room size is desired, a smaller dimension for the unit section may be used, or a half size section (10 1/2") provided. This, however, will require changing the sill and roof parts to compensate for it. The length selected for these sections will conform to the standardized ceiling height, for example 8' 4".

When the size of the wall unit has been determined, the spacing of the fastening holes for securing the wall sections to the sills and plates is readily fixed, also the spacing of the floor beams and roof rafters. With the unit dimension adopted as 1' 9" the floor beam and rafter spacings may conveniently be made four times this length, or 7', and as this determines the length of the longest piece of wood which is to be employed, as these wooden parts may be made to size in the mill, it is apparent that little wastage of lumber is likely to be had where the rough lumber employed is of the proper size. These short floor timbers also make it possible to employ lumber of narrower widths than customarily employed for supporting the floors according to

usual form of building construction further lessening this cost as well as the over all height of the building to obtain the same overhead clearances and ceiling heights.

- 5 In order to facilitate erection and to provide for various sizes of windows, door openings, archways and the like, the wall and partition forming sections may be made up to occupy the width of one, two, three or four unit sections. With the 10 1' 9" unit section, these multiple unit sections are 3' 6", 5' 3" and 7' wide.
- In the planning of buildings of the character referred to, the walls and partitions are generally laid out at right angles to one another so that all 15 angles are 90°. The analyses of such a floor plan will show that it can be resolved into a few simple, and more or less typical basic quantities. The outside walls of the building consist of inside and outside corners connected together by straight 20 continuous portions of wall; and in some cases a porch or entry is provided outside the building proper. The partitions join the wall at some straight portion of the wall or at an inside corner and continue straight to either another outside 25 wall, or to a corner, or to another partition wall at right angles to it. Additional partitions may start from the first partitions mentioned. To provide a completely flexible system of interchangeable parts, it is necessary to meet all these 30 conditions.

The present invention therefore contemplates the provision of wall forming sections which in addition to being of unit width and multiples thereof, are provided with side members whereby 35 the sections may be readily assembled together to meet any condition which may arise in the regular right angled layout or floor plan. It also contemplates an arrangement whereby bay windows and corners at 45° may be obtained.

40 A further object of the invention is to so design the side members of these wall sections that the desired variations for the complete units may be had by combining a much lesser number of structural shapes to make the units, and by inverting certain of the units, or turning them right or left. This materially reduces the stock required and the manufacturing cost.

These wall sections or units are, as has been stated, of rectangular shape. According to the 50 present invention each wall and partition section or unit is made up of top and bottom members preferably of steel and welded together. Each of these members is formed to a shape to give added strength and is provided with holes, fittings 55 and the like for securing the sections to the plates, sill or floor as well as securing them to one another, and securing the insulation board to the inside and outside of the walls and both sides of the partitions and securely interlocking the corners formed by such insulation board.

Where the sections or units are to embody door or window openings and the like, the frames for these openings may be welded into place and designed to receive suitable metal trim whereby the desired finish may be had and the edges of the insulation board covered and secured in place.

Other and further objects of the invention will be pointed out as the description proceeds:

70 The accompanying drawings show, for purposes of illustrating the invention, an arrangement of interchangeable standardized parts for producing an entire building, it being understood the drawings are illustrative of the invention and 75 are not limiting the same.

In these drawings:

Figure 1 is an elevation of a one and one-half story residence;

Figure 2 is a floor plan for the building Figure 1;

Figure 2a is a perspective view of the wall and partition system of the building of Figure 2;

Figure 2b is an enlarged view showing a fragment of cross section paper suitable for laying out floor plans to scale;

Figure 3 is a fragmentary perspective view to illustrate the placing of a sill on the foundation and the securing of a wall forming unit to the sill;

Figure 4 is a horizontal sectional view to illustrate the formation of inside and outside corners and the junctions of partitions with one another and with outside walls;

Figures 5a to 5v, inclusive, are diagrams illustrating the shape and character of wall and partition sections or units of various widths and for various purposes;

Figures 6a to 6h, inclusive, are sectional views taken on a plane such as 6—6 through any of the single width wall and partition sections or units of Figure 5a and showing a system of side members for the frames in suitable combinations for being connected together to form the various connections;

Figure 6k is a view similar to Figure 6a but taken through a double width section or unit;

Figure 6l is a sectional view through a frame for joining an oblique portion to a wall or partition;

Figure 7 is a tabulation indicating the manner in which units having the character shown in Figures 5a-5v inclusive are provided with the various side member combinations of Figures 6a-6k inclusive, whether these units are reversible (R) or whether such units are to be constructed both right and left handed, indicated r and l respectively;

Figure 8 is a fragmentary horizontal section through a door opening, such as at 8—8 in Figure 5i and showing the insulation board and trim in place;

Figures 9 and 10 are fragmentary vertical and horizontal sectional views on the lines 9 and 10 respectively of Figure 5d to illustrate the formation of the window frame, and showing the insulation board and trim in place;

Figure 11 is an isometric view illustrating the formation of an exterior outside corner, with insulation board and stucco in place;

Figure 12 is a similar view showing two exterior inside corners, one furnished in stucco, the other in brick, and a partition connected opposite this corner;

Figure 13 shows a fragment of a side member of a wall unit and loose washer;

Figure 14 illustrates a split pin adapted for securing the side members of adjacent units together and made in various lengths;

Figures 15 and 15a illustrate insulation board securing nails, also made in various lengths;

Figure 16 illustrates a reinforcing bar employed to stiffen the frames where desired;

Figures 17 and 17a illustrate a wire anchor member for securing stucco, brick or stone to the wall and also made in various lengths;

Figure 18 is a horizontal sectional view through a building corner and illustrates the furring out of space for conduits, pipes and the like, also strips for securing together the edges

of the insulation boards forming an outside corner of the building;

Figure 19 is an enlarged view of the corner forming member for the furred out corner;

5 Figure 20 is a section on the line 20-20 of Figure 19;

Figure 21 is a sectional view showing two walls at right angles to one another connected by a diagonal corner-forming wall provided with an 10 archway;

Figure 22 is an enlarged view of the 135° junction;

Figure 23 is an enlarged sectional view of an adapter for the 135° connection between two 15 walls;

Figure 24 is a sectional view illustrating the joining of an oblique inside partition to another wall;

Figure 25 is a perspective view indicating an 20 outside wall arrangement with inside and outside corners, the placing of partitions and floors, etc.;

Figure 26 is a fragmentary perspective view of a portion of straight wall showing the joining together of two units such as shown in Figure 6d 25 (or the middle of a double width unit as in Figure 6k) and the securing of the outside and inside insulation to the same, the insulation extending across the junction;

Figure 27 is a view similar to Figure 26, illustrating the use of a retaining strip where the 30 edges of the insulation boards are opposite a junction in a straight wall;

Figure 28 is a perspective view of the insulation retaining strip;

35 Figure 29 is a perspective view, parts being broken away, to show the foundation, sill, first floor, first story walls, plate, second floor, second story walls, roof plate, second story ceiling (third floor) and fragment of roof rafter;

40 Figures 30a and 30b are perspective views illustrating the fastening of wooden exteriors to the frames;

Figure 30c illustrates the insulation securing nail-in place;

45 Figure 31 is a perspective view illustrating three different floor beam sections with supporting partitions;

Figure 32 is a perspective view illustrating a form of floor beam for special uses;

50 Figure 33 is a diagrammatic elevational view of a gable;

Figure 34 is a horizontal sectional view through a wall section for forming gables or other walls where no provisions are made for the joining of 55 partitions;

Figure 35 is a sectional view illustrating the securing of a rafter or stair stringer to the vertical members of a side wall or gable; and

Figure 36 shows a modified form of nail receiving hole.

Planning the building

Figure 1 shows an elevational view of a one and one-half story house and Figure 2 a floor plan for this building. This floor plan indicates the layout of outside walls, partitions, doors and windows in a conventional manner with all the walls and partitions at right angles to one another and designed so that the length of all walls and partitions are multiples of a unit length, such as the 1' 9" dimension above referred to.

In laying out the plan one uses paper, ruled as indicated in Figure 2b. It has dotted cross lines 5 forming squares 1' 9" to scale and pairs of 75 parallel lines 6 adjacent each cross line 5 to indi-

cate wall thickness. The center lines of the partitions and walls are placed on the dotted cross lines 5. With the system of wall and partition units to be described, a wall or partition may be placed along any of these lines, and the size and relative location of rooms, partitions, and the like varied in an indefinite manner, and the floor plan is readily understood.

The floor plan of Figure 2 and perspective of Figure 2a illustrate the facility with which the layout may be made and the ability to provide halls of convenient width, closets of varying sizes, as well as rooms of any desired size.

The dwelling shown is 47' 3" x 36' 9" from center line to center line of the farthest outside walls, and has an entry—E—3' 6" x 5' 3", a living room—L—21' x 14', sun parlor—S—10' 6" x 10' 6", dining alcove—D—7' x 7', kitchen—K—10' 6" x 10' 6", rear bedroom—BR—10' 6" x 10' 6", bathroom—BR'—7' x 7', front bedroom—BR"—14' x 14' with bay window together with closets —CL—which are 1' x 9" x 3' 6", 3' 6" x 3' 6", and 3' 6" x 5' 3", and halls—H—3' 6" interconnecting the rooms, these distances being from center line to center line of the partition and walls. The floor plan also indicates the inside and outside corners, outside doors, inside doors, archways and windows of four different widths, and the use of a built in chimney and fire place independent of the wall units.

The foundation sill and floor

The foundation for the building is indicated at 10 in Figures 3 and 29. It may be of any suitable form of masonry of the proper size to accommodate the sill, insulation covering and exterior finish employed. It may be provided with a wooden nailing strip 10', if desired. The sill is preferably in the form of a steel channel 11 resting on its side as shown. These channels are 35 preferably formed of plate stock (approximately $\frac{1}{2}$ " thick) folded to shape and cut with mitred corners as indicated at 12 in Figure 29. The sill members are secured together by suitable corner blocks and bolts, the latter being indicated at 13, Figure 29. These sill forming channels are 40 provided with rows of holes spaced in predetermined manners for securing the floor system and wall system in place and may be stiffened by inserting blocks 14 between their flanges, as shown 45 in Figure 3.

The floor system is shown in Figures 25 and 29. Referring first to Figure 2, it will be seen that the floor plan bears vertical lines 15 spaced apart the width of four units or 7'. These lines 55 are intended to indicate the location of the floor beams which are parallel to one another and spaced 7' apart. One of these floor beams is indicated at 15 in Figures 25 and 29. Various shaped beams may be employed but the preferred 60 form consists of two steel sections, 15a and 15b, with their webs secured together back to back. These members have a top flange 15' and lower flange 15" spaced apart to receive wooden sleepers 16 which may be cut in the mill to the exact size required. Their ends are cut to fit in the same form as the joints (51) in the second floor construction of Figure 29. The flanges 15' and 15" are punched with holes indicated at 17 to receive nails for securing the sleepers in place, 65 and at 24c to receive partition units. The metal beams 15 are cut away below the flange 15" adjacent to ends to accommodate the foundation, or the foundation may be built to accommodate the full depth of the beams. The ends of the 70 75

beams 15, pass between the top and bottom walls of the sill channel 11 and are secured to the sill by angles 18 as indicated. This stiffens the sills and replaces the stiffening blocks 14 at these points. The upper surface of the sleepers 16 are at the same level as the upper face of the sills. Sills and plates are punched to receive all connections for structural members. There are holes provided at 7' on centers to receive connections of metal floor beams 15, ceiling beams and roof rafters. The first beam is to be set 7' 1 1/4" from corner and all others 7' on centers. Floor timbers 16 are fastened at 1' 2" on centers, except the first one adjoining sill or plate where the distance is to be 3 1/2" from center of wall. Next 10 1/2" from the center of the first one and 1' 2" on center after that. Length of floor beam is exactly 6' 11 1/2" and the dimensions calculated to support 50 lbs. of live load to the square foot are 20 1 3/4" x 4 3/4". This size is ample and gives a very large factor of safety without being cross braced.

The wall and partition system

The wall and partition system, according to the present invention, consists of a plurality of rectangular metal frame pieces or units of predetermined width and uniform height secured together and preferably covered on both sides with a suitable "fabric" such as insulation board. These wall units are made of a standard width and multiples thereof (adjusted to compensate for wall thicknesses as explained below) and provided with side or vertical members adapted to be fitted together to provide the corners and junctions necessary. They are made plain or are provided with window frames, doorways, or archways, etc.

Figures 5a to 5v inclusive diagrammatically illustrate a system of wall units as follows: 5a, 5c, 40 5k, and 5o are plain units; 5b is a single width unit with window; 5d, 5e, 5f, and 5g are double width units having various window arrangements; 5h, 5i, and 5j are double width units having various door and arch arrangements; 5l and 5m are 45 triple width units with windows; 5n is a triple width unit with an archway; 5p, 5q, 5r, 5s, 5t, and 5u are quadruple width units with various window arrangements; and 5v is a quadruple width unit with archway.

Figures 6a to 6h inclusive, indicate the cross section of the vertical or side members of a system of these units adapted for building up the walls and partitions. These vertical or side members are made of relatively heavy strip sheet 55 steel (or aluminum) (about $\frac{3}{16}$ " thick) which may be folded by suitable forming dies to the desired shape. The shapes employed have adequate rigidity as columns and are capable of securement together and to the insulating board.

The sixteen ends on the eight shapes shown in these Figures (6a-6h inclusive) comprise members of four different outlines. The side members 20 (Figures 6a, 6b, and 6c) are of channel shape with a narrow side 20a with holes 20b, a 60 wide side 20c, with three rows of holes 20d, and a connecting web 20e. The ends of the web are flanged in as indicated at 20f. The side members 21 (Figures 6a, 6f, and 6g) have narrow sides 21a and 21b and a zig-zag connecting web 21c. 65 Holes are provided as indicated at 21d, 21e, and 21f and the ends of the web are flanged in as indicated at 21g. The members 20 and 21 are particularly designed to form, when joined, an outside or an inside corner.

70 The side members 22 (Figures 6b, 6d, 6f, and

6h) have sides 22a and 22b and a web 22c with a central portion displaced laterally as indicated. The sides and web have rows of holes as indicated at 22d, 22e, 22f, and 22g. The ends of the webs 22c are flanged in as indicated at 5 22h. The side member 22 is designed especially to facilitate joining units together to form a straight wall or partition to provide intermediate vertical members in multiple width units, and, when used in pairs to provide for joining in a 10 partition (or wall) at right angles.

The side members 23 (Figures 6c, 6e, 6g, and 6h) have sides 23a and 23b (like the sides 22a and 22b of members 22) and a web portion 23c characterized by a fin 23d formed by folding the sheet 15 metal flat on itself. This fin does not extend the entire length of the side member, being cut away for a purpose to be described. The sides 23a and 23b and fin 23d have holes indicated at 20 23e, 23f, and 23g. The ends of the web portion 23 are flanged in as indicated at 23h. The members 23 are designed particularly for making junctions with the members 22.

The sides or flanges of the channel shaped members 20, 21, 22, and 23 have, in addition to the round holes (20b, 20d, 21e, 22e, 22f, 23f, 23g) specially formed holes 25 adapted to receive serrated nails. The holes 25 are made by slitting two tongues 25a and 25b out of the channel and pressing them inwardly as shown in Figures 26, 30 30a, 30b, and 30c. They are preferably located halfway between the round holes.

The spacing of the flanges or sides of the channel members 20, 21, 22, and 23 is uniform so that the thicknesses of the frames may be the same. The frames are completed by top and bottom channel members 24 of uniform cross section. The sides of these channel members are indicated at 24a and the bottom at 24b. They are made by forming suitable sheet metal to shape, which is then cut to the proper length for the unit section with which the piece is to be used. These top and bottom members preferably extend the entire width of the frame. The sides or flanges of the side channel members 20, 21, 22, and 23 45 being cut away top and bottom to accommodate the side 24a of the top and bottom channel members 24, as indicated in Figures 3, 11, and 12. The end flanges 20f, 21g, 22h, and 23h are welded to the inside of the webs 24b of the top and bottom channels, and the corners of all the frames are reinforced by gusset plates shown at 26.

The wall and partition units of multiple width are made up with side members of the same shape and in the same combinations as the single width units, and have top and bottom channel members of the same shape. Figure 6k shows a double width unit having the same side members as Figure 6a. In the middle it is provided with two vertical members 22-22, identical with the members 22 of Figures 6b, 6d, 6f, and 6h. These members are secured together by rivets 27 and act to stiffen the frame, provide a support for the insulation to be applied and provide a slot for joining with other units or sections having 60 the fin 23d.

The sides of the channels 24 have rows of holes 24d similar to holes 25 while the webs of the channels 24 are provided with holes spaced according to a predetermined pattern with respect to the center lines of the squares to be formed by each unit section (or multiple section) and corresponding holes are provided in the upper side of the sill frame members 11, and floor beams 15. Such holes are indicated at 65 24c. 70 75

These holes are spaced $5\frac{1}{4}$ " apart and make it possible to readily secure the frames to the top of the sill and to a plate 28 of channel shape. This spacing of these holes allows one to secure the frames close together as shown in the drawings or to space them apart $5\frac{1}{4}$ " (or a multiple thereof), thereby reducing the expense of non-bearing partitions and allowing greater flexibility in room size, window and door spacing, etc.

10 The side members which are intended to be fastened together (20, 21, 22, 23) are provided with holes, above referred to, and spaced according to a predetermined pattern so that these side members may be secured together in the desired relations and without cutting or fitting. The fin 23d is cut short to accommodate the top and bottom channels 24.

Various forms of securing means may be employed, (such as bolts or rivets) but to facilitate assembly, one may use a split pin such as shown at 29 in Figure 14. This split pin is passed through the holes in the adjacent side members of the frame units and bent back on itself like a split cotter pin. An anvil block 30 (see Figure 13) may be used, if desired, to receive the bent ends of the split pin. A special tool is to be employed for this operation.

If additional reinforcing be desired at the joints, a stiffening member may be secured to the frame members in such a way as not to increase the fixed dimensions of the unit. Such a stiffening member, designed for use adjacent the members 22, is shown at 31 in Figures 12 and 16. It has holes aligned with the holes in the webs 35 of the members 22 and is secured to them by long pins 29.

The frame for the partition forming units generally has a fin 23d at the end adjacent the outer wall. This fin passes between two members 22, as shown in Figures 4 and 12, and is secured in place by pins 29 passed through the aligned holes.

Where the partitions extend across the floor system, they are secured directly to the sleepers and floor beams, a suitable filler or spacer being employed. Wherever the beam bears on a partition or other wall, it is of the depth of the sill, or plate with which it is used so that the upper level of the beam is even with the lower surface of the upper flange of the sill or plate. In case 50 the floor beam is used in spaces where there is no support from below and it is necessary for structural reasons to increase the depth of the beam (as shown in Figures 29 and 31), there is no interference with partitions or walls where 55 the added depth is present. This merely projects downwardly below the level of the sill or plate. The ends of the beams with deepened sections are cut off where they join the sill or plate, or rest of a partition so that the parts all fit together, as shown in Figure 31. Where an inside corner appears on the first floor plan opposite a second story floor beam of deepened section, the end of this floor beam is cut away so as to match or fit adjacent the plate or shallow floor beam 60 resting on the same partition or wall. Hence uniform spacing is available between the top of the sill and beams of one floor and the bottom of the plate and such beams of the second floor as rest on partition units and wall units. In 65 some cases where the beam is directly over a partition, and no other portion rests directly on it, the floor beam may have the modified section shown at 50" in Figures 2a, 31, and 32.

75 Inasmuch as the wall and partition system

must provide windows, doorways, archways and the like, the wall units are designed to permit building into specified units, a variety of frames suitable for the same. These openings may be designed so as to employ the side members 20, 21, 22, or 23.

Figure 8 is a fragmentary sectional view illustrating the side jamb of a door frame, employed in a unit such as 5h, 5i, 5j, 5n, or 5v. These door and archway carrying sections are employed in units of two, three or four unit widths, so that doorways and archways of conventional size are available.

The side members of these units are of any of the forms above described (20, 21, 22, or 23) depending on where they are interposed in the wall and partition arrangement. The top channel 24 is also the same, but the bottom channel is either cut away entirely across the opening or the sides of the channels removed. Vertical channel members 32 are secured at their lower ends to the bottom channels 24 in the same way as the side channel of the frame members. The channels 32 have sides 32a and 32b provided with holes 32c spaced the same as the holes 22e and 22f of channel 22, and are adapted for use in securing the insulation in place. The web 32d may have holes spaced the same as the holes 22d and 22g so that the strips 32 may be substituted for the strips 22 where junctions with other partitions are not needed. The web 32d is also provided with tapped holes to receive screws 33 whereby stop forming members 34 and metal trim 35 may be secured in place. The trim has a suitable ornamental shape and provides the stop for the door. The trim 35' for an archway is shown in Figure 21. The top of the door opening may be formed of the same parts as the sides, if desired.

The formation of the window openings and frames is shown in Figures 9 and 10. The sides or stiles of these openings are formed by channels 32 like the door openings. The tops and bottoms are formed by horizontal strips 36-36 as shown in Figure 9. The end strips 36 are preferably welded to the channels (20, 21, 22, or 23) and the stiles welded to the strips 36. The window frame itself has side members 37, a top member 38 and a sill forming member 39, secured to the strips 32 and 36 forming the opening. The sill 39 extends outwardly beyond the 50 stucco 59 or other finish and sheet metal trim strips 40 and 41 complete the exterior finish of the opening. The window sash is shown at 42 and inside trim at 43 and 44.

Certain of the units or sections may be turned right or left or inverted, and hence need not be made right-handed or left-handed. Other units are not capable of being used in this way, and must be made both right-handed and left-handed. Figure 7 indicates the manner in which the units are made. The columns 5c-5v inclusive indicate the form of unit (Figures 5a-5v inclusive) the horizontal lines 6a-6k inclusive refer to the combinations of side members of Figures 6a-6k inclusive. (R) indicates that the unit need be made in one form only while (r and l) indicate that the unit is made both right- and left-handed. Units such as 5b, 5d, 5e, 5m, 5p, 5s have windows extending substantially their entire widths and hence cannot be used in corners. They need therefore to be made only in units of d type adapted for use in straight walls.

The wall and partition units or sections are covered inside and outside by large sheets or

panels of insulating board I (say $\frac{3}{4}$ " thick), pre-cut to the proper length and width for the purpose intended. They may be provided with rows of holes adjacent the side edges spaced according to such a pattern as will fit the round holes of the channels 20, 22, 23, and 32, and secured in place by nails 55' passed through these holes. The preferred construction, however, utilizes the serrated nails 55 of Figure 15. These nails are driven through the insulation board and the holes 25, and the serrations prevent the withdrawal of the nails. The use of the serrated nails is indicated in Figures 8, 26, and 30c, but it is to be understood that some such securing means is to be employed for the entire outer insulating board. The other half of the partition insulating board may be similarly secured in place. Before the inside wall board and the rest of the partition board is applied electrical wiring may be completed and later closed in.

Insulation board suitable for the purposes of the present invention may be manufactured from the fibres of wood, sugar cane, and the like. Board of this nature is commonly employed in building constructions for purposes of insulation and as a base for plaster. It has the property of forming a reinforcement for the frames, an outer and inner wall surface, insulation against heat and cold, and is sound proof and fire retarding. This board is, of course, cut where window and door openings are to be formed.

Where the joint between two adjacent insulation boards comes opposite a junction formed by two members such as 22, a retaining strip 56 is employed to hold these edges close together as shown in Figure 27. This strip is secured in place by being hooked to pins 29 which pass through the holes 22d of the two adjacent members. This strip is used both inside and outside as occasion arises. At the outside corners the edges of the insulation board are secured together and to the frame by corner anchor strips 57, see Figure 18, or may be nailed directly to the member 20.

45 It will be noted from the assemblies shown in Figures 4, 11, 12, that the metal parts are designed to accommodate the insulating board in such a way that the margin of one of the boards at each corner is locked in place between two metal frame members. Where both edges of an insulating board fit into channels the board is trimmed away as shown at 57' in Figure 4.

The wall construction, whereby a smooth surface of insulating board is provided, is adaptable to be finished in a variety of manners. The joints may be covered and the surface painted, or stucco or brick veneer may be applied. Where these finishes are to be employed some form of anchorage is preferred, such for example as anchor shown in Figures 17 and 17a. These anchorages are made of galvanized wire and looped at the end 58' so as to receive the nail 55 which secures the insulation board in place. The free end of the wire is embedded in the stucco, or inserted into the mortar between the bricks or stone. A stucco surfacing is indicated at 59 in Figures 4, 9, 11, 12, 18, and brick at 60 in Figure 12.

70 Where a wooden exterior, such as shingle, clapboards and the like is required, the wall is provided with wooden strips such as shown at 61 in Figures 30a and 30b. The shingles or clapboards may be fastened directly to these strips as indicated in Figure 30b, or to insulation board

as shown in Figure 30a. These are secured in place by pins 55" which are driven through the holes in the frame members 22. These strips are placed horizontally for shingles and vertically for clapboards.

5 Where the design of the building makes it desirable to have a portion of a wall which does not conform to the scheme available with the interchangeable wall sections, it is possible to insert an ordinary wooden panel, securing it in a 10 convenient manner to the sill plate and adjacent wall or partition sections. Furthermore the designer is able to readily accommodate a chimney such as shown at 63 in Figure 2.

The selection of units to be used is simple, as 15 it requires merely the following out of a very few principles. For instance, where an outside corner for outside wall is desired, and walls continue from the corner for any distance more than 1', select a wall unit with style shown on Figure 6b 20 and one of the style of Figure 6f. Then if walls continue in a straight line from the end of the corner forming unit selected add as many style 6d units as are necessary together with a 6b or 6f unit to complete such side of the wall. The 25 same method of selection is followed for the remaining corners. If it is necessary to form an outside-inside corner where no partitions are to be connected or continued with either of the outside walls, use styles 6b and 6f where walls 30 continue from inside corner for more than 7'. The distance from inside to outside corner can be a single unit width 1' 9", or a multiple thereof, up to 7' in which case single units with styles shown on Figure 6a are to be used. As to the selection 35 of windows and doors, the selection of same depends on the design of the building. The styles in all cases are to be selected according to the above instructions, as units having windows, arches and doors are built with the same styles 40 as shown on Figures 6a to 6k inclusive, and made right- and left-hand for use on opposite position.

45 Where walls are to be attached to other walls at right angles and for the formation of the various inside partitions, the styles provided will afford all kinds of combinations. Connections can be made to any inside or outside wall at any point selected so long as the unit dimension is complied with. Between two walls, use style 6e 50 from 1' 9" to 7' in width. Above that width use two units of style 6h and sufficient units of style 6d to complete the wall or partition. If doors, archways, etc., are desired then use the units with archways, doorways, etc., having the 55 desired connecting styles as above indicated.

It is to be noted that all the multiple width blank wall units 5c and 5k and 5o employ the arrangement of pairs of vertical members 22 spaced 1' 9" apart. These members, as well as other members 22 are punched with three rows of holes, the holes of each row being spaced regularly (say 1' 4" apart vertically). The center set of holes 22g are to be used to connect adjacent members together either by rivets 27 or pins 29. The other two sets of the holes 22d are left to connect other wall units at right angles or for covering strips 56. All the connections will be made with units having end members 23 as the tongue or fin formed by this member will fit exactly in the groove formed by any two members 22. Holes 23e on tongue 23d shown on style 6e are punched to fit holes 22d of style 6d.

70 Holes on top and bottom members of channels 24 for the frames are standard punched to fit 75

holes punched on sills, plates and floor beams 15. They are spaced as follows: From corner member left of 6a, 6½" measured from outside of frame and all other holes spaced 10½" on centers. Distance of holes on corner member shown on Fig. 6a right is 4" measured from the frame and then 10½" on centers. Where the thickness of the metal parts of the wall is 2½", the adjustments to compensate for wall thicknesses are: Units 10 having connections shown on Figure 6a will be 1' 9" and the multiple thereof up to 7'. Units 15 6b and 6c will be 1½" longer, making them 1' 10¼", 3' 7¼", 5' 4¼", and 7' 1¼". All the 6f and 6g units will be 1½" shorter, or 1' 7¾", 5' 1¾", and 6' 10¾". The difference is for the 20 half thickness of outside wall which is to be added as measurements are to be taken always from the center line. This will account also for the difference of distance of punching at one end of the 25 corner units.

Figures 18-20 indicate a form of construction whereby a corner may be furred out to provide a passageway for pipes or the like. A strip 65 is secured in the space formed between the two 25 frame side members 22 and projects inwardly. Another spacing strip 66 is secured to the top and bottom channels 24 of the lower section. Insulation boards 67 and 68 are secured to these strips and to a corner forming device 69. This device 30 is composed of channels 70 adapted to receive insulation and angle pieces 71, which may be secured to the floor system and ceiling pieces and clamped by bolts 72.

Where an outside corner of 135° is to be formed, 35 the parts are designed so as to fit a diagonal of one of the regular units of the checkerboard design and special wall units are required. Instead of having side members 21, 22 or 23 as previously discussed, they may employ channels 20 turned 40 90° as shown in Figures 21 and 22. This channel 20 is secured to a narrow unit or frame 14 having a connecting side member 75 adapted to fit the flange 20a, as shown, and an opposite side member 32 the same as shown for the doorway, 45 Figure 8, or a length of side member 22 may be used. The width of the frames 14 are such as to form a space which equals the width of a double width unit of the type shown in Figure 6d. This section may be provided with an archway as 50 shown, the same reference characters being used for the corresponding parts in Figure 8.

The outside insulation boards 76 and 77 are secured to the frames by anchorage strips 78 adapted to enter the space between the flange 55 20c and the portion 75a of member 75. This member is zig-zag as shown to provide an interlock with the channel 20 and provide a trough 75b to receive the edge of the insulation board 79.

Where the 135° or 45° angle is to occur inside, 60 a section 80, as shown in Figures 6f and 24, is employed. It has a side channel 81 with fin 23d adapted to fit between two channels 22, as indicated, and a side channel 32 like that previously 65 described, or it may use a channel 22 where desired. Its length is such that two of the units and a regular 6d unit may make a diagonal of a square two units wide.

Where the diagonals (Figures 21-24) are to cross a different number of squares it is, of course, 70 obvious that the width of the filling in units (74 and 80) will be varied.

When the various frames or wall units have been erected on the sill and secured together, the 75 erection may be carried to the second floor or roof, as the case may be. The floor system

for the second floor is substantially the same as for the first floor, except that the metal beams 50 and joists 51 may be somewhat lighter than the corresponding parts for the first floor. They are secured to the plate 28 in the same way as discussed with respect to the first floor. The plate 28 may be a roof plate or may support a second story. The second story wall and partition system is made up out of units of the same character as used in the first story wall, but they may be arranged in entirely different manners, and there may be setbacks or overhangs if desired.

The upper ends of the units forming the wall system for the second story are secured to a roof plate 52 as indicated in Figures 25 and 29, and this plate may carry metal beams 53 and joists 54 forming the ceiling for the second story. These beams and joists may be still lighter than those for the second floor. A form of steel rafter is indicated in Figure 29 at 81 and securing bracket 20 at 86.

The gable

The gable is merely a variation of wall construction and uses a modified form of unit of the style used in the wall. A typical layout for the gable is shown in Figures 33 and 34. The sections or units 85 are of the standard width or multiple thereof and have lower ends and sides like the corresponding parts of the wall sections. Side members may be of style 22 or 32. Windows may be included as indicated. The tops of the frames for the gables will, of course, have to be formed at the proper angle for the roof design desired, and cut to the proper length for the place intended.

Stair stringers, gable rafters or any other device may be secured to the vertical members of the wall sections by hook shaped members such as indicated at 96 in Figure 35.

It will, of course, be understood that both the floor system and wall system may be employed in a building or that only one of these systems may be employed with certain advantages flowing from the use of the same. It is also apparent that the insulation board may be left off of the inside of the wall or the outside of the wall or from one or both sides of the partitions, and other forms of wall and partition surfacing employed, where all the advantages of the double thickness of insulation and dead air space are not required.

What is claimed is:

1. In building construction, a wall or partition forming unit having a rectangular frame with rigid top and bottom members and side members, each formed of sheet metal formed to a channel shaped cross section, the flanges of the channels extending inwardly from the edges of the frame, one of the side channels of the frame having a transverse web, a wide flange and a narrow flange, the flanges having regularly spaced holes.

2. In building construction, a wall or partition forming unit having a rectangular frame with rigid top and bottom members and side members, each formed of sheet metal formed to a channel shaped cross section, the flanges of the channels extending inwardly from the edges of the frame, one of the side channels of the frame having a zig-zag web portion and narrow flanges each having regularly spaced holes.

3. In building construction, a wall or partition forming unit having a rectangular frame with rigid top and bottom members and side members, each formed of sheet metal formed to a

channel shaped cross section, the flanges of the channels extending inwardly from the edges of the frame, one of the side channels of the frame having narrow flanges and a web having a central, outwardly displaced portion, the web having three sets of regularly spaced holes, one set being in the central displaced portion, the other sets being on the opposite sides of the central portion, the flanges also having regularly spaced holes.

4. In building construction, a wall or partition forming unit having a rectangular frame with rigid top and bottom members and side members, each formed of sheet metal formed to a channel shaped cross section, the flanges of the channels extending inwardly from the edges of the frame, each of the side channels of the frame having narrow flanges and a web having a central, outwardly displaced portion, the web having three sets of regularly spaced holes, one set being in the central displaced portion, the other sets being on the opposite sides of the central portion, the flanges also having regularly spaced holes.

5. In building construction, a wall or partition forming unit having a rectangular frame with rigid top and bottom members and side members, each formed of sheet metal formed to a channel shaped cross section, the flanges of the channels extending inwardly from the edges of the frame, one of the side channels of this frame having a web portion provided with an outwardly projecting fin extending lengthwise of the side channel member and having its ends cut shorter than said side channel member, the flanges and web having regularly spaced holes.

6. In building construction, a wall or partition forming unit having a rectangular frame with rigid top and bottom members and side members, each formed of sheet metal formed to a channel shaped cross section, the flanges of the channels extending inwardly from the edges of the frame, each of the side channels of this frame having a web portion provided with an outwardly projecting fin extending lengthwise of the side channel member and having its ends cut shorter than said side channel member, the flanges and web having regularly spaced holes.

7. A wall or partition forming unit having a frame as claimed in claim 1, wherein the other side channel of the frame has a zig zag portion and narrow flanges with regularly spaced holes.

8. A wall or partition forming unit having a frame as claimed in claim 1, wherein the other side channel of the frame has narrow flanges and a web with a centrally outwardly displaced portion and narrow flanges, the web having three sets of regularly spaced holes, one set being in the centrally displaced portion, the other sets being in the opposite sides of the central portion, the flanges also having regularly spaced holes.

9. A wall or partition forming unit having a frame as claimed in claim 1, wherein the other side channel of the frame has a web portion provided with an outwardly projecting fin extending lengthwise of the side channel member, the side channels and web having regularly spaced holes.

10. A wall or partition forming unit having a frame as claimed in claim 2, wherein the other side channel of the frame has one of the side channels of the frame having narrow flanges and a web with a centrally outwardly displaced portion, the web having three sets of regularly spaced holes, one set being in the central displaced portion, the other sets being on the opposite

sides of the central portion, the flanges also having regularly spaced holes.

11. A wall or partition forming unit having a frame as claimed in claim 2, wherein one of the side channels of this frame has a web portion provided with an outwardly projecting fin extending lengthwise of the side channel member and having its ends cut shorter than said side channel member, the flanges and web having regularly spaced holes.

12. A wall or partition forming unit having a frame as claimed in claim 3, wherein one of the side channels of this frame has a web portion provided with an outwardly projecting fin extending lengthwise of the side channel member and having its ends cut shorter than said side channel member, the flanges and web having regularly spaced holes.

13. In building construction, a wall or partition forming unit having a rectangular frame with rigid top and bottom and side members each formed of sheet metal formed to channel shaped cross section, the flanges of the channels extending inwardly from the edges of the frame, and reinforcing column-forming elements extending lengthwise of the frames, the columns being formed of channel shaped strips of sheet metal secured together back to back and having side flanges in the planes of the side flanges of the side members, the channel shaped strips having centrally displaced portions so as to form vertical open slots between the same.

14. A corner construction for buildings, comprising two vertical rectangular frames at right angles and arranged to form a butt-joint, the frame forming the outside of the corner having a side member of channel shaped cross section with the web at right angles to the flanges, the other frame forming the inside of the corner being of channel shape cross section and having a zig zag web portion one part of which is in contact with the inner flange of the first member, the other part being spaced from said inner flange of the first member, and securing means passing through the adjacent web and flange.

15. In a system of interchangeable rectangular metal frames for forming walls and partitions, a side member comprising a channel shaped metal strip having a flat web forming the vertical edge of the frame and inwardly extending side walls parallel with one another forming side faces for the frame, the side walls of the channel shaped strip being provided with apertures spaced according to a predetermined pattern for securing one side wall of the member to insulation board extending along one face of the frame and for securing the other side wall of the member to another frame extending at right angles to the first frame and to insulation board extending along the other face of the frame.

16. In combination, two like metal members adapted to form a sill or plate at right angles to one another to form a corner, the upper faces of the members being provided with a series of holes uniformly spaced lengthwise thereof, the holes being symmetrical with respect to a center line extending lengthwise of the members and spaced the same uniform distance from the intersection of said center lines, and two wall forming frames having their adjacent vertical edges secured together at the corner, the bottom member of each frame having holes spaced the same as the holes in the sill forming members, and securing means passed through the holes.

17. A corner construction for buildings com-

prising two fixedly supported rectangular metal frames, each having side members of channel cross section, the flanges of one channel and web and one flange of the other channel forming the 5 outside of the corner, the web of the first channel being zig zag, one portion thereof being secured to the second flange of the said other channel, the other portion being spaced therefrom.

18. In a building, two walls at right angles to 10 one another each wall being formed by metal frames having vertical channel shaped members with the sides of the channels parallel with the plane of the corresponding wall, the web of one channel having an outer portion in contact with 15 the adjacent flange of the other channel and a portion spaced from said flange, and means for securing the two channels together.

19. In a building, two walls at right angles to 20 one another each wall being formed by metal frames having vertical channel shaped members with the sides of the channels parallel with the plane of the corresponding wall, the web of one channel having an outer portion in contact with 25 the adjacent flange of the other channel and a portion spaced from said flange, means for securing the two channels together, surfacing material secured to each of the frames on the outside of the corner, and surfacing secured to each 30 of the frames, on the inside of the corner, one portion of the inner surfacing material entering into the space provided between the channels.

20. In a building, two walls at right angles to 35 one another each wall being formed by metal frames having vertical channel shaped members with the sides of the channels parallel with the plane of the corresponding wall, the web of one channel having an outer portion in contact with 40 the adjacent flange of the other channel and a portion spaced from said flange, means for securing the two channels together, two insulating boards one fastened to the inside of each of 45 the frames, the edge of one of the latter mentioned boards entering the space provided between the channels, the edge of the other being close to its face.

21. In a building, two walls at right angles to 50 one another each wall being formed by metal frames having vertical channel shaped members with the sides of the channels parallel with the plane of the corresponding wall, the web of one channel having an outer portion in contact with 55 the adjacent flange of the other channel and a portion spaced from said flange, means for securing the two channels together, an anchorage strip secured to the outside flange of the second channel the strip extending beyond the web and being bent to have two free edge portions, one parallel with the web and the other parallel with the 60 flange, and insulating boards having their edges received in the spaces formed by the anchorage strip.

22. In building construction, in a straight wall, 65 two vertical channel shaped members arranged back to back, the central portions of the webs thereof being displaced towards one another to form a vertical channel between the margins of the webs, means passing through said central portions for securing the channels together, and 70 a wall forming unit having a vertical fin along the side thereof inserted into the channel and secured in place therein.

23. In building construction, in a straight wall, 75 two vertical channel shaped members arranged back to back, the central portions of the webs

thereof being displaced towards one another to form a vertical channel between the margins of the webs, means passing through said central portions for securing the channels together, and a wall forming unit having a side member with a body portion and a long narrow fin inserted in the channel and secured in place therein, the width of the fin being such as to space the body of the side member away from the sides of the first channel shaped members. 5

24. In building construction, in a straight wall, two vertical channel shaped members arranged back to back, the central portions of the webs thereof being displaced towards one another to form a vertical channel between the margins of 15 the webs, means passing through said central portions for securing the channels together, a wall forming unit having a side member with a body portion and a long narrow fin inserted in the channel and secured in place therein, the width 20 of the fin being such as to space the body of the side member away from the sides of the first channel shaped members, and wall surfacing material secured to the sides of the first channel shaped member and entering the said spaces. 25

25. In building construction, in a straight wall, two vertical channel shaped members arranged back to back, the central portions of the webs thereof being displaced towards one another to form a vertical channel between the margins of 30 the webs, means passing through said central portions for securing the channels together, two insulating boards secured to the channel shaped members to form surfacing for the wall, the boards having a joint opposite the vertical channel, and a retaining strip passing between the 35 boards and entering the channel and means to fasten the retaining strip in place.

26. In building construction, the combination 40 with a suitable support or foundation, of a metallic sill or plate extending thereabout and of channel shaped cross-section resting on one side of the channel and facing inwardly, and a floor system comprising metal beams having ends received within the channels of opposite portions 45 of the sill or plate, the beams having side channels, and floor timbers having ends received in the side channels of the beams and in the sill or plate forming channel and secured in place 50 therein.

27. In building construction, a support, a metal sill of channel shaped cross-section extending around the support to define the shape of the building and formed by folding sheet metal to 55 shape, the channel facing inwardly, a beam extending between two parallel parts of the sill and parallel with another part of the sill, the ends of the beam extending into the sill channel, the beams having oppositely facing channels and a web deeper than the width of the channels and 60 floor beam channels. 60

28. A floor system for buildings comprising a sill forming metal channel extending about the building, and a plurality of parallel metal beams at right angles to adjacent portions of the sill and parallel to other portions of the sill, the metal beams being formed of two channel shaped sheet metal members secured together back to back, the sill and beam channels having regularly spaced holes, wooden floor timbers having 70 their ends extending into sill and beam channels, and securing means passing through the holes and into the timbers. 65
